UNITED STATES PATENT OFFICE.

LEO STEVENS, OF NEW YORK, N. Y.

CONTROLLABLE BALLOON.

SPECIFICATION forming part of Letters Patent No. 661,826, dated November 13, 1900.

(Application filed February 7, 1900. Serial No. 4,386. No model.)

To all whom it may concern:

Be it known that I, LEO STEVENS, a citizen of the United States, and a resident of the city of New York, borough of Manhattan, in the county and State of New York, have invented a new and Improved Controllable Balloon, of which the following is a full, clear, and exact description.

This invention relates to certain improvements in the construction and arrangements of parts by which I am enabled to provide an effective controllable balloon, a car being provided for carrying passengers and freight and the car having propelling and steering devices for guiding the movement of the balloon, a gas-envelop and parachute attachment being provided to sustain the car.

This specification is the disclosure of one form of the invention, while the claims define the actual scope thereof.

Reference is to be had to the accompanying drawings, forming a part of this specification, in which similar characters of reference indicate corresponding parts in all the views.

Figure 1 is a perspective view of the invention. Fig. 2 is a detail section of the gearing of one of the propellers. Fig. 3 is a plan view of the car, and Fig. 4 is a front elevation of the apparatus.

The gas bag or envelop 5 may be of any desired construction and is preferably of the shape shown. This bag is covered by netting, and to the netting are attached a number of ropes or cords 6, which pass downward from the gas-bag and are joined to a longitudinally-disposed beam 7, whereby the beam is supported from the gas-bag. Owing to the connection of the ropes or cords 6 with the beam 7 and gas-bag 5 the gas-bag is held with a certain degree of rigidity and caused always to lie in approximate parallelism with the beam. Attached to certain of the ropes or cords 6 and situated beneath the gas-bag 5 is a parachute 8, which is elongated longitudinally of the machine and curved transversely, so as to present a concave under side. This parachute is stayed or guyed by ropes or cords 9, passing from its side edges downward and inward to the beam 7. The parachute is thus held in parallelism with the beam and with the gas-bag. As the balloon moves ahead or astern in the plane of the parachute 8 the

parachute will offer no resistance to the movement of the balloon; but should the balloon begin to drop the parachute will tend to retard this movement and will insure a gradual fall of the apparatus even should control of the balloon be entirely lost.

Connected rigidly with the beam 7 by means of a suitable framing 10 is a car 11, which is preferably elongated, as shown, and which may be of any desired construction, provided with doors and windows, as shown. Within this car 11 is contained a suitable motor, (not shown,) which serves to drive a bow propeller 12 and side propellers 14. The bow propeller 12 is carried on a suitable shaft 15, passing into the car and suitably connected with the motor. As shown in Fig. 2, the side propellers 14 are respectively carried on short shafts 16, mounted on ball-bearings 17 in a tubular frame-piece 18, rigidly connected with the car 11 by braces 19. These shafts 16 respectively carry bevel-gears 20, meshing with like gears 21 on shafts 22. The shafts 22 are mounted on ball-bearings 23 in a tubular frame-piece 24, and the frame-pieces 24 and 18 are connected by a gear-case 25, covering the gears 20 and 21. The shafts 22 are connected with the motor within the car 11 in any suitable manner, so as to be driven thereby. The propellers 12 and 14 serve to propel the balloon, causing it to move through the air, the apparatus being suspended meanwhile by the gas-bag 5. The balloon is guided upward or downward by means of a weight 26, which is mounted in any suitable manner to slide longitudinally on the beam 7. This weight is provided at each end with a rope or cord 27, the ropes passing over sheaves 28, attached, respectively, to the ends of the beam 7, and from these sheaves 28 the ropes 27 pass down into the car 11. By means of the ropes 27 the weight 26 may be moved along the beam. Should the weight 26 be moved ahead, it is clear that it will depress the bow or front of the apparatus, thus inclining downward the parachute 8. Then as the balloon is propelled ahead the parachute will cause the apparatus to move to a lower plane. Should it be desired to elevate the apparatus, the weight 26 should be moved rearward, thus depressing the stern of the apparatus, and forward movement thereof will result in raising the balloon. The

balloon may be steered toward each side by a rudder 29, which may be constructed of any suitable material sufficiently light and strong. I prefer to construct the rudder of sail-cloth, 5 fastened at its foot to a support 30 and at its head to a spar 31, the former being pivotally attached to the stern of the car 11 and the latter being pivotally attached to the rear end of the beam 7. Ropes or cords 32 are attached 10 to the outer end of the spar 30 and led forwardly to sheaves 33, respectively carried by the gear-cases 25, and from these sheaves 33 the ropes 32 pass into the car 11, where they may be connected with any suitable mechanism 15 for operating them. By throwing the rudder to one side or the other it is clear that the balloon may be guided sidewise in either direction.

It will be understood that all of the parts 20 of this apparatus should be constructed of the lightest possible material consistent with the necessary strength. I do not limit myself to the material or to the manner of constructing these elements. For example, the 25 parachute 8 may be constructed of a light sheathing of aluminum or of a stout frame having canvas strained over it. The beam 7 may be tubular, if desired, or it may be constructed solid of a light material. Also 30 the framing 10 is preferably formed of tubular sections suitably joined. Various parts of the apparatus are preferably constructed with easily-detachable joints, facilitating disconnecting the parts for stowing and transporting them. This will also enable the apparatus to be set up in operative adjustment 35 at any point desired without requiring the use of a workshop or the like.

Having thus described my invention, I

claim as new and desire to secure by Letters 40 Patent—

1. In aerial navigation, the combination of a gas-bag, a parachute mounted below the same, a beam suspended from the gas-bag below the parachute, a car supported from the beam, propelling devices carried by the car, and a weight mounted on the beam and adjustable longitudinally thereof, for the purpose specified.

2. A controllable balloon, comprising a gas-envelop, a rigid beam arranged below the same and extending longitudinally thereof, flexible connections between the gas-envelop and the beam to sustain the beam from the gas-envelop, a parachute, the middle portion 55 of which is fastened to the said connections, the parachute extending outward from opposite sides thereof, connections between the side edges of the parachute and the said beam, and a car provided with driving and controlling devices, the car being supported from the beam.

3. A controllable balloon, comprising a car, a beam mounted above the same and extending longitudinally thereof, means for rigidly 65 connecting the beam with the car, an elongated gas-envelop arranged above the beam and extending longitudinally thereof, and flexible connections between the beam and gas-envelop, for the purpose specified.

In testimony whereof I have signed my name to this specification in the presence of two subscribing witnesses.

LEO STEVENS. [L. S.]
